UNITED STATES PATENT OFFICE.

THOMAS TERRELL, OF LONDON, ENGLAND.

BICYCLE-BRAKE.

SPECIFICATION forming part of Letters Patent No. 600,459, dated March 8, 1898.

Application filed November 29, 1895. Serial No. 570,456. (No model.) Patented in England October 29, 1895, No. 20,336.

To all whom it may concern:

Be it known that I, THOMAS TERRELL, gentleman, a subject of the Queen of Great Britain, residing at 15 St. Petersburg Place, Bayswater Road, London, England, have invented new and useful Improvements in Brakes for Pneumatic-Tired Wheels, of which the following is a specification, and for which I have obtained Letters Patent of Great Britain, dated the 29th day of October, 1895, and numbered 20,336.

This invention has relation to brakes to be used in connection with the pneumatic-tired wheels of cycles and common road-vehicles, and has for one of its objects a more efficient brake, and for another object the prevention of injury to the tire; and it consists in employing as a retarding medium a pliant or flexible apron, strip, or band of leather or fabric mounted upon the spring-arms of a frame arranged to circumferentially follow and envelop, when in operation, but normally (and when out of use) to stand away from the periphery of a tire.

Figure 1 of the accompanying drawings represents a safety-bicycle provided with a brake constructed and arranged in accordance with my improvements. Fig. 2 represents the fore part of the bicycle upon an enlarged scale.

Fig. 3 represents the rear portion of the machine, showing a part of the brake, which consists, essentially, of an inner end-supported spring metallic frame with the free-ended spring-arms secured within the opposite edges of a brake band or apron made of any suitable material, such as leather or canvas, and adapted, when brought down upon the tire, to first only touch the extreme outer circumference of the same and then as the pressure increases for its opposite edges to gradually fall from the said center to the sides and thus invest or envelop the tire periphery to a greater or less degree, proportional to the said pressure applied. Fig. 4 represents a top side plan of a portion of the handle-bars, showing the position of the brake-lever. Fig. 5 represents a back elevation of Fig. 3, showing the apron of the brake in section and how the bifurcated lower end of the brake-rod is

made to span the apron and is connected to the two opposite sides or spring-arms of the same, so that when the said sides are de-

pressed or descend to a lower plane than the extreme outer circumference of the tire the brake fore part, whose normal breadth is 55 greater than the inner part, is gathered in laterally and made to fall to and invest the tire's periphery. Fig. 6 represents a top side plan of the brake, with one side of the same in section, thus showing one of the spring-arms of the frame which carries the apron. Fig. 7 represents a side elevation of Fig. 6; and Fig. 8 represents a like view as Fig. 7, but with the brake brought slightly down and with the tip of its free end just touching the 65 periphery of the tire and the other part. Fig. 9 represents the brake investing or enveloping the tire to its fullest extent. Fig. 10 represents a cross-section upon the dotted line x , Fig. 7, with some of the parts removed; 70 and Fig. 11 is a section upon the dotted line x' , Fig. 9. Fig. 12 represents a section of Fig. 2 upon the dotted line x^2 , showing the clip for connecting part of the fluid-conducting pipe to the framing member. Fig. 13 represents a modified form of bifurcated bracket. Fig. 14 represents my brake operated by an ordinary brake-rod and applied to the front wheel of a bicycle; and Fig. 15 represents, upon a larger scale, the connection between 75 brake-lever and sides of the brake.

In Figs. 1 to 12, a is the brake, consisting of a strip or apron of leather or other flexible material a' , circumferentially following the contour of the outer periphery of the tire 85 b and supported or carried at its outer edges by arms or spring-arms a^2 , connected together by a cross end a^3 , hinged to side brackets a^4 , affixed by clips or otherwise to the back forks c' of the general framing c of the machine. 90 The outer and free end a^5 of the spring-framing is much broader than the inner end a^6 , and this said inner part has a cross end a^3 , which turns about the connection bracket-arms a^4 as fulcrum.

Located above and spanning the brake sides is an arched bar or yoke d' , centrally connected to the lower end of a brake-rod d and having its extremities connected, respectively, with the divergent spring-arms a^2 , to which 100 the curved longitudinal edges of the brake-apron a' are secured. The extremities of the arched bar or yoke are preferably connected to the two divergent spring-arms a^2 through

the medium of pivoted lugs i^7 . The other end of the said rod d passes up the middle of a fixed barrel or cylinder e , made fast by clips or other connection means to the backstays 5 of the machine and having leading into its upper end a pipe or passage f . The said inner end of the rod d terminates in a pump-bucket piston d^2 , made up of a cup-leather d^3 , having located within its cup an expanding 10 rubber washer d^4 , expanded by the turning of a screw d^5 , coming upon the top of a metal washer d^6 . By such an arrangement the piston is made at all times to truly fit the inside of the barrel. Located within the said cylinder e and coming at the back of the piston and surrounding the piston-rod is a counter-balancing-spring g .

The conducting-pipe runs along the top tube of the framing and is secured thereto 20 by clips h , having rubber linings for preventing the contact of metal to metal, while the fore end of the said pipe is fitted with a flexible connection f' to admit of the steering-post i turning within the socket or head i^2 of 25 the machine. This flexible-connection pipe f' is secured to the tail end j of the nozzle k' of a forcing barrel or cylinder k , trunnion-mounted at k^2 to a bracket i' on the post i and having working within it a pump-bucket 30 or other piston m , connected with and terminating a piston-rod m' , which works through the end cap k^3 and has its upper end connected to the boss or junction n' of the brake-lever n , which is pivoted at n^2 to a bracket n^3 , 35 carried by the handle-bars n^4 , surrounding the steering-post i . By drawing the handle n upward the piston is depressed, the cylinder k slightly rocked, and the water or other fluid substance o coming below the said piston within the said cylinder k is forced outwardly through the nozzle k' and rearwardly through the connection f' and pipe f , from which it enters the barrel or cylinder e above the piston d^3 , and through the pressure exerted by the displaced fluid the piston d^2 is 45 forced down the cylinder e in opposition to the force of the spring g , carrying with it the brake-rod d , which, through the arched bar or yoke d' , forces the two divergent spring-arms a^2 , with the brake-apron a' , in a downward direction and causes contact between the brake-apron and tire, first at the tip or outer extremity and then practically throughout the area of the brake-apron, until the tire 50 is partially wrapped by the brake-apron, as will be understood by reference to Fig. 9. On hand-pressure on the brake-lever being relieved the counterbalancing-spring now expends its pent-up energy created by its former compression in returning the whole of 55 the parts to their normal positions, while the brake-frame is taken from contact with the wheel partly by the retrograde movement of the piston-rod.

60 In Fig. 13, which represents a modified form of the bifurcated bracket bridging and carrying the brake and located at the lower end of

the brake-rod, d' is the arched bar or yoke, made from spring metal, carrying at its free ends the enveloping brake a , while it is jointedly connected to the brake-rod d by a link d^7 . By making the said bifurcated bracket of sheet-steel or of spring metal the tire is more efficiently invested by the brake.

In Figs. 14 and 15, which represent my investing or enveloping brake operated by an ordinary brake-rod and applied to the front wheel of a bicycle, c is a part bicycle-frame; n^4 , the handle-bar; b' , the front wheel; n , the brake-lever; n' , the brake-rod, to the lower end n^2 of which the enveloping brake a , which is fulcrumed and supported at c^6 by brackets a^4 , connected to the fork c' , is jointedly or slidingly connected, so as to admit of the angular movement of the brake when its operating-rod moves vertically. n^3 is the spring for returning the brake and its lever to their normal positions.

It will be seen that in the practical operation of my improved brake the arms at each side of the piece of leather or other pliant material will be under longitudinal tension and that the leather or pliant material will be under transverse tension.

Having fully described my invention, what I desire to claim and secure by Letters Patent is—

1. The combination with a wheel-tire, of a flexible brake-apron extending circumferentially of the tire and following the contour thereof, a pair of laterally elastic or yielding spring-arms secured respectively to the curved, longitudinal edges of the flexible brake-apron to normally hold it extended or stretched laterally and adapted when depressed to embrace the tire, a bracket to which the spring-arms are hinged at one end, and means for swinging the spring-arms on their hinged ends as a center, substantially as described.

2. The combination with a wheel-tire, of a flexible brake-apron extending circumferentially of the tire and following the contour thereof, two laterally elastic or yielding spring-arms secured respectively to the curved, longitudinal edges of the flexible brake-apron to normally hold it extended or stretched laterally and connected at one end by a cross-piece, a bracket in which the said cross-piece of the spring-arms is mounted, and means for moving the spring-arms in the arc of a circle to and from the wheel-tire, substantially as described.

3. The combination with a wheel-tire, of a flexible brake-apron which increases in width from one end portion to the opposite end portion and extends circumferentially of the tire and follows the contour thereof, two laterally elastic or yielding spring-arms hinged at one end, diverging from such hinged end and secured to the curved, longitudinal edges of the said brake-apron to normally hold the latter extended or stretched laterally, and means for swinging the divergent spring-arms in the arc

of a circle on their hinged end as a center, substantially as described.

4. The combination with a wheel-tire, of a flexible brake-apron extending circumferentially of the tire and following the contour thereof, two spring-arms extending along and secured to the longitudinal edges of the brake-apron, a bracket or support on which the spring-arms are mounted at one end, an arched bar or yoke spanning the brake-apron and secured at its extremities to the two spring-arms, a brake-rod connected to the central portion of the arched bar or yoke, and means for operating the brake-rod to move the brake-apron to and from the wheel-tire, substantially as described.

5. In enveloping brakes for pneumatic-tired wheels, the combination with a pliant strip of enveloping material, broader at its outer end

than at its inner one, of spring-arms connected to its opposite edges and normally holding said pliant strip extended or stretched laterally, substantially as and for the purpose described and illustrated.

6. A brake for a wheel consisting of a piece of leather or other pliant material attached to arms at each side and so arranged that when the brake is applied the arms shall be under longitudinal tension and the leather or pliant material shall be under transverse tension. 30

In testimony whereof I have hereunto set my hand in presence of two subscribing witnesses.
